UNITED STATES PATENT OFFICE.

AARON RATNER, OF NEW YORK, N. Y.

DISH-WASHING MACHINE.

1,311,179.

Specification of Letters Patent. Patented July 29, 1919.

Application filed September 7, 1918. Serial No. 253,008.

To all whom it may concern:

Be it known that I, AARON RATNER, a citizen of the United States, residing at Bronx borougn, in the county of Bronx and State of New York, have invented certain new and useful Improvements in Dish-Washing Machines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in mechanical dish-washing machinery; and, the invention has reference, more particularly, to a novel construction of apparatus for use in restaurants, hotels, homes and in all other places wherein the functions of the machine find utility.

The invention has for its principal object to provide a novel construction of mechanical dish-washing machine providing a maximum of capacity in a very compact space, by means of which the dishes and table cutlery may be quickly, easily and safely cleansed with a minimum of physical effort, and with an appreciable saving of time.

A further object of the invention is to provide a novel mechanical dish-washing machine with a plurality of removable dish-racks or containers, so arranged and related to the mechanism that the same are easily passed by the operation of the mechanism successively through the tank containing the hot cleansing water, without any swinging motion; and in such maintained upright position that all danger of the dishes or other contents thereof being thrown out or too violently agitated, tending to loss through breakage, is eliminated, and at the same time the said dishes and other contents are presented most effectively to the swirling and cleansing effects of the water.

Other objects of the present invention, not at this time more particularly enumerated, will be clearly understood from the following detailed description of the same.

With the various objects of the present invention in view, the same consists, primarily, in the novel construction of mechanical dish-washing machine hereinafter

set forth; and, furthermore, this invention 55 consists in the novel arrangements and combinations of the various devices and parts, as well as in the details of the construction thereof, all of which will be hereinafter more fully described, and then finally embodied in the claims appended to said specification.

The invention is clearly illustrated in the accompanying drawings, in which:—

Figure 1 is a front end elevation of the 65 novel construction of mechanical dish-washing machine, made according to and embodying the principles of my present invention.

Fig. 2 is a top or plan view of the same. 70

Fig. 3 is a detail vertical longitudinal section of the same, taken on line 3—3 in said Fig. 2.

Fig. 4 is a detail transverse section of the same, drawn on an enlarged scale, and taken 75 on line 4—4 in said Fig. 2.

Fig. 5 is a detail transverse section of one of the removable dish carrying racks or containers, drawn on an enlarged scale, and arranged to carry plates, saucers and the 80 like; Fig. 6 is a similar view showing the application of mesh containers or baskets to said racks for the support of table cutlery, etc.; Fig. 7 is a similar view showing the dish carrying rack as arranged to support 85 cups, drinking glasses, etc.; and Fig. 8 is a detail longitudinal section of the latter arrangement, taken on line 8—8 in said Fig. 7.

Similar characters of reference are employed in all of the hereinabove described 90 views, to indicate corresponding parts.

Referring now to the said drawings, the reference character 1 indicates a suitable tank for holding hot water, said tank 1 being supported by any suitable form of 95 standard or frame-work 2, which, however, is preferably made of angle-iron, so as to provide both strength and durable wearing qualities.

The said tank 1 is preferably open at the 100 top, and journaled in suitable bearing brackets 3, attached to its end walls, is a longitudinally disposed shaft 4, which extends through the interior of the said tank. Fixed upon one of the exteriorly projecting ends 105 of said shaft is a crank-handle 5 whereby the machine may be manipulated by hand, although it will be readily understood that

- any suitable means for rotating said shaft by mechanical power may be provided if desired.
- 5   Mounted on said shaft 4, within said tank 1 are a pair of spider-frames 6 having a plurality of radiating arms 7, said spider-frames being spaced longitudinally apart so that they are positioned, one adjacent to each end wall of said tank.
- 10   Secured upon an inwardly projecting hub 8 connected with one of said bearing brackets 3 is a fixed gear 9 which is thus positioned adjacent to one of said spider-frames 6.
- 15   The reference character 10 indicates rectangular carrying frames which are respectively disposed between the free ends of longitudinally opposite arms 7 of said spider-frames. Each carrying-frame is provided at its ends with journal-portions 11 which are journaled in the said free ends of arms 7. Fixed on an outwardly projecting end of one of said journal-portions 11 at one end of each carrying-frame is a gear 12 for 20 rotating said carrying-frame. Connected with each arm 7 of said spider-frame 6, adjacent to the fixed gear 9, and located upon each said arm 7 between said fixed gear 9 and said carrying-frame gear 12, is an outwardly projecting stud 13, upon which is loosely mounted to rotate thereon an idler gear 14, which meshes mutually with said fixed gear 9 and the adjacent carrying-frame gear 12.
- 30   Each carrying-frame 10, thus rotatably mounted between the free ends of the arms 7 of said spider-frames 6, is adapted to receive and carry a removable dish-carrying rack or container. Each of said dish-carrying racks 40 or containers comprises a pair of end-members 15 interconnected by longitudinally extending rods 16, which provide support for the articles arranged within the rack or container, and yet, owing to their open or 45 spaced arrangement freely permit cleansing water to sluice between and in cleansing contact with said articles. Each end-member 15 of said racks or containers is provided adjacent to its upper marginal edge with a hand-hole 17, in which the hands may be engaged to grasp the racks or containers, for the purpose of lifting the same into and out of operative relation to the carrying-frames, and for carrying the racks or containers 50 from place to place. Projecting outwardly from the end-members 15 of said racks or containers are pairs of studs 18, which when the racks or containers are inserted within the rectangular inclosures of the carrying-frames 10, engage and rest upon the lateral end bars of said carrying-frames, thereby supporting said racks or containers in operative suspended or supported relation to said carrying-frames, as will be understood. The 55 longitudinal side bars of said carrying-frames serve to engage the sides of said racks or containers and thus prevent any accidental lateral displacement of the same from properly supported relation to said carrying-frames.
- 70   Referring more particularly to Fig. 5 of the drawings, I have illustrated therein a preferred interior arrangement of rack or container adapted to support plates, saucers and the like. Such arrangement comprises 75 additional longitudinal rods 19 extending at the sides between said end-members 15. Lateral bars 20 having notched ends 21 are hooked over said rods 19 so as to extend laterally between the same, said bars 20 being 80 spaced apart by means of spacing sleeves 22 arranged on the rods 19 between the ends of the bars 20. This spaced arrangement of lateral bars 20 provides a plurality of compartments in which plates 23, or the like 85 may be disposed edgewise or upright throughout the interior of the rack or container, in such manner that each plate is independently supported and guarded against knocking against the adjoining plates during the washing operation.
- 85   Referring more particularly to Fig. 6 of the drawings, I have illustrated therein a preferred interior arrangement of rack or container adapted to support or carry silverware, table cutlery and the like. Such arrangement comprises the above described longitudinal rods 19, lateral bars 20 and spacing sleeves 22, the latter, however, being of a size to space the lateral bars 20 a little 90 farther apart. The spaced arrangement of the lateral bars provides a plurality of compartments in which wire-mesh baskets 24 may be inserted, the latter being so arranged 95 as to support and carry in upright position 100 a plurality of knives, forks, spoons and similar articles 25, which are to be washed, the open mesh of the baskets easily permits the cleansing water to sluice therethrough in cleansing engagement with said articles 25. 105 If so desired the interior of said baskets may be partitioned transversely with mesh partitions 26 to assure the holding of articles 25 in the desired upright position as shown.
- 110   Referring more particularly to Figs. 7 and 8 of the drawings, I have illustrated therein a preferred interior arrangement of rack or container adapted to support or carry cups, drinking glasses and similar articles. Such arrangement comprises a plurality of longitudinal rods 27 serving as supports, and longitudinal side rods 28 serving as side guards. Extending between a pair of laterally opposite side rods 28 are cross guards 29. The said parts 27, 28 and 115 29, thus arranged, provide compartments at the bottom of the container or rack adapted to receive and support drinking glasses 30 or similar articles. Additional 120 longitudinally extending rods 31 are pro- 125 130

vided at each side adjacent to the upper part of said rack or container for the support of a removable top rack. Said removable top rack comprises end members 32 having shoulders 33 for engaging said rods 31. Extending longitudinally between lower marginal edges of said end members 32 are supporting rods 34, and above the same are arranged longitudinal side guard rods 35. Extending between the laterally opposite outer side guard rods 35 are cross guards 36. The said parts 34, 35 and 36, thus arranged, provide compartments in said top rack adapted to receive and support cups 37 or similar articles, which may be locked in place by removable longitudinal rods 37'.

Arranged in connection with said framework 2, beneath said tank 1, are suitably disposed supporting cradles 38, upon which extra containers or racks may be stored. Also connected with the sides of said framework 2, are cradle brackets 39, which also serve to hold extra containers or racks. The said cradle brackets 39 are preferably hinged or pivotally connected with said framework 2, so that the same may be folded back against the latter when not in use. When said cradle brackets 39 are operatively extended or opened out, hooks 40 are provided for holding the same in such operative position.

In using the novel dish-washing machine thus constructed, the racks or containers are loaded with the soiled dishes, etc., and then placed in the carrying-frames 10 so as to be suspended between the free ends of the arms 7 of the spider-frame 6. The tank 1 being filled with hot water, by turning the crank-handle 5 the shaft 4 is rotated. Since the spider-frames 6 are fast on the shaft 4, the rotation of said shaft also rotates the spider-frames so that the racks or containers are carried around and successively passed through the hot water. The hot water sluices through the open racks or containers in and around the contents of the latter, thus washing off the dirt and grease from the dishes, etc. Since each carrying-frame 10 is in geared relation to the fixed gear 9, it follows, that, as the spider-frames revolve, the idler gears 14 travel around the fixed gear 9, and are thus rotated. The rotation of the idler gears 14 is in turn transmitted to the carrying-frame gears 12, which, being the same size as the fixed gear 9, make one revolution for each revolution of the shaft 4 and spider-frames 6. The effect of this mechanical movement is to always maintain the carrying-frames 10 horizontal while the same are revolved with the spider-frames 6, and consequently the racks or containers supported by said carrying-frames 10 are maintained in upright position at all times, so that there is no swinging oscillation

of the same. The dishes are therefore easily held in the containers or racks against undue agitation or violent movement, and are always properly presented to the effects of the hot water sluicing around the same with cleansing effect. The above described sun and planet arrangement of gearing for thus controlling and holding the containers or racks upright at all times while being revolved with the spider-frames 6, also makes for an exceedingly compact arrangement, permitting the spacing of the containers or racks closely together, and thus permitting a saving of bulk as to the complete machine, and economizing the amount of water necessary for efficient operation. A further advantage of the arrangement is the ease with which it may be operated, the racks or containers nicely balancing one another, and since their movements are synchronous with each other, undue vibration or jars, tending to accidental injury of their contents is quite eliminated.

The racks or containers, as arranged with the novel carrying-frames, are removable, with ease and speed, there being no fastening, locks or catches necessary to be manually operated. The racks or containers are interchangeable so that extra racks or containers for various sized dishes may be available, and may serve to hold the dishes while drying, and also may be used to store the dishes away.

I am aware that some changes may be made in the general arrangements and combinations of the several devices and parts, as well as in the details of the construction of the same, without departing from the scope of my invention as set forth in the foregoing specification, and as defined in the claims appended thereto. Hence, I do not limit my invention to the exact arrangements and combinations of the various devices and parts as herein set forth, nor do I confine myself to the exact details of the construction of the said parts as illustrated in the accompanying drawings.

I claim:

1. A dish-washing machine, comprising a tank, a rotatable main frame within said tank, rotatable dish-supporting means journaled in connection with said main frame, and a transmission mechanism operated by the rotation of said main frame for rotating said dish-supporting means so as to hold the latter continuously upright in horizontal position while the same are revolved with said main frame.

2. A dish-washing machine, comprising a tank, a rotatable shaft journaled to extend through said tank, radiating arms connected with said shaft, dish-supporting means journaled to extend between the free ends of longitudinally opposite radiating arms, a central fixed or sun gear in axial alignment

with said shaft, a planet gear of the same size as said fixed or sun gear connected with each dish-supporting means, and idler gears mounted on said radiating arms to mesh 5 mutually with said fixed or sun gear and the adjacent planet gear for the purposes described.

3. A dish-washing machine, comprising a tank, a rotatable main frame within said 10 tank, rotatable dish-supporting means journaled in connection with said main frame, a central stationary gear in axial alinement with said main frame, and transmission mechanism operated from said stationary 15 gear by the rotation of said main frame for producing a synchronous independent and complete revolution of said dish-supporting means in company with each revolution of said main frame for the purposes described.
- 20 4. A dish-washing machine, comprising a tank, a rotatable shaft journaled to extend through said tank, means for rotating said shaft, spider-frames having radiating arms fixed on said shaft, rectangular carrying- 25 frames having journals at their ends journaled in the free ends of longitudinally opposite arms of said spider-frames, a carrying-frame gear fixed on one journal of each carrying-frame, a central fixed gear of the

same size as said carrying-frame gear adjacent to one spider-frame and axially alined with said shaft, idler gears mounted on the arms of said last mentioned spider-frame to mesh mutually with said fixed gear and an adjacent carrying-frame gear, and demountable dish-holding racks adapted to be operatively supported by and associated with said carrying-frames.

5. A dish-washing machine, comprising a tank, a rotatable main frame having radiating arms within said tank, rectangular carrying-frames journaled upon and between the arms of said main frame, means producing a rotation of said carrying-frames relative to each rotation of said main frame to hold said carrying-frames in constant horizontal position while revolving with said main frame, and demountable dish-holding racks adapted to be let down into the embrace of said carrying-frames in supported 45 relation thereto.

In testimony that I claim the invention set forth above I have hereunto set my hand this 4th day of September, 1918.

AARON RATNER.
